HARRY LEVISON, OF SAN FRANCISCO, CALIFORNIA

ADJUSTABLE CLAMP

Application filed August 9, 1929. Serial No. 384,716.

My invention relates to the mounting of printing plates such as electrotypes, stereotypes, zinc etchings, half tones or any other plate which is to be positioned on a support upon either wooden, composition or metallic blocks. Further, my invention relates to the securing of a plate within the usual means as a chase for mounting an assembly or form for printing in a press, in such a manner that the position of the mounted and secured plate can be varied within the chase or other means utilized for securing the assembly in a press, after the form has been substantially completed. More particularly, my invention relates to the detachable mounting of the plate on a supporting block and to the positioning of the mounted plate within a chase or other form retaining means.

Printing plates have, heretofore, usually been permanently attached to the mounting blocks, or if they have been detached from the mounting blocks, the usual means provided for securing them to the blocks has been extremely complicated and undesirably expensive. After the plate was secured to the blocks, its position could not be changed relative to the other matter within the form, without undesirably effecting the whole set-up.

In general, it is the object of my invention to provide means whereby a printing plate may be readily attached in a positive manner to a separate block and which will enable the position of the secured plate to be positively determined and changed without varying the locking means utilized for positioning the plate in the chase.

Another object of my invention is the provision of means adapted to secure the plate to a block in combination with other means for varying the relationship between the plate securing means and the usual press furniture.

A further object of my invention is the provision in combination with a chase, furniture, a block, means for securing the block within the chase, of means for simultaneously securing a printing plate to the block and means for varying the position of the

plate and block securing means with respect to the chase and furniture.

My invention possesses other advantageous features, some of which with the foregoing will be set forth at length in the following description of my invention. It is to be understood that I do not limit myself to the showing made by the description, as I may adopt various forms of my invention within the scope of the claims, which are to be accorded a range of equivalents consistent with the state of the prior art.

Referring to the drawings:

Figure 1 is a plan view of a chase, a printing plate, the clamping means by which the block and printing plate are simultaneously secured in position, and the means which are utilized for varying the relative position of the block with respect to the chase.

Figure 2 is a view in transverse section along the line 2—2 of Fig. 1.

Figure 3 is a plan view of the clamping means employed.

Figure 4 is a section along the line 4—4 of Fig. 3, showing the construction of the clamping means and of a means for varying the position of the plate relative to the chase.

Figure 5 is a plan view of a chase, a printing plate, the means used for clamping the plate within the chase, and the means for varying the position of the plate relative to the chase, after the plate has been secured and locked in position within the chase.

Figure 6 is a transverse section along the line 6—6 of Fig. 5.

Figure 7 is a view in side elevation, partly in section, of a form of the clamping means employed.

Figure 8 is a plan view of a base utilized in conjunction with the clamping means.

Figure 9 is a modification of the base utilized with the clamping means.

Briefly, my invention may be characterized as comprising the provision of means for adjusting the position of a printing plate within such a positioning device as a chase, after the chase has been locked. This adjusting means is conveniently provided in combination with the clip disclosed in my co-pending application Serial Number

251,029, filed February 1, 1928, and entitled "Clamping means for mounting printing plates".

In printing, it is desirable to secure a positioning of the printing plate within the chase, in a very exact manner. Thus, in color work, it is expedient that exact and true *régistry* of the plate be possible. Accordingly it is desirable that a variation 10 of the position of the plate be possible within the chase. Heretofore, this variation has been effected by inserting and removing shims such as pieces of paper or metal from about the furniture or block used to position 15 the plate. Such a method is more or less unexact and requires a loosening of the locking means, thus releasing the whole set-up within the chase.

In my aforementioned co-pending application, I have described the combination of a block 11, having a groove or channel 12 extending thereabout, which is adapted to receive and to engage a projection or *teat* 13, provided upon a clip 14. The clip usually 25 has an inwardly extending lip 16, which is adapted to engage bevelled edge 17 provided upon the printing plate, and is so formed that upon a movement of the clip parallel to the plane of the printing plate, it positively 30 secures and positively engages the plate against the block.

In accordance with my invention, I provide means for adjusting the position of the joined plate and block, after they have been 35 locked in position in the chase by suitable locking means as quoins 18. Preferably, I form this adjusting means by attaching a bolt 21 to the clip so that the bolt is rotatable with respect to the clip. This I have 40 accomplished by forming a boss 22, which is deformed into a suitable aperture 23, provided in the clip. The bolt is provided with a suitable head 24, adapted to receive a wrench or other means so that rotation of the 45 bolt is readily effected with respect to the clip. A threaded base 26, usually of a square shape, is provided which is adapted to receive the bolt 21. In practice, the base is abutted against furniture 27, the clamp is 50 engaged with the blocks and with the printing plate and the assembly is locked within the chase by use of the quoins. When it is found that the position of the plates is unsuitable and that a variation within the limits 55 provided by the clamp is desirable, the alternate loosening and tightening of oppositely positioned clamps, will serve to move the printing plate to the desired position. This movement is accomplished without the 60 loosening of the quoins and without the danger of displacing the other matter in the form as type, furniture, etc., from their generally desired position.

In certain printing operations, it is sometimes 65 desirable to position the plate angu-

larly with respect to the chase. In such an instance, reference is usually had to various angularly shaped pieces of wooden furniture, and the final securing of the plate within the chase is more or less the work of a carpenter. 70 Such a positioning is extremely undesirable since it does not possess the flexibility desired, nor is it accurate to the *dégrée* necessary to produce the very best printing jobs. 75 Further, as speed is of the essence in printing jobs, such operations, which are time consuming because of the inexactness, are most undesirable. In the several figures, namely Figures 5 to 9 inclusive, I have illustrated a manner of modifying my aforementioned clamp so that it may be utilized 80 to position unmounted printing plates angularly within a chase. In this connection, I have expediently employed a base 41, upon which is rotatably mounted a nut 42. This nut is adapted to receive the bolt 21 which is joined to the clip so that the plate can be both angularly and adjustably positioned. 85

As I have illustrated in Figs. 5 and 6, the clips with the bases I have just described, are positioned within a chase in combination with suitable furniture, in such a manner that the plate is angularly positioned with respect to the chase, and so that it is at the same time secured to the block upon which it is to be mounted. Angular displacement of the several bases is prevented by the insertion of suitable pieces of furniture 44, in such a manner that the side-thrust of the 95 bases is distributed to the chase. 100

By alternately loosening and tightening the several clamping means, the position of the printing plate within the chase can be varied to meet the conditions under which it is to be utilized, after the furniture, the printing plate and the clamp have all been positioned and positively secured in the approximate desired location within the chase. In this manner, the mounting of the printing plate within the chase is accomplished so 110 that the plate is not only positively positioned very quickly, but its subsequent position can be varied to meet exactly the conditions desired in operation. 115

The base 41 is conveniently provided of a metal strip, bent to enclose the nut. The swivel mounting of the nut with respect to the base, is effected by the position of pins 43, which are joined to the nut and extend therefrom into the base in which they are received in apertures. 120

The stresses of securing the plate within the chase, and of positioning it positively upon the base, are transmitted from the nut to the base largely by the pins 43. In some 125 instances, I have found it desirable to form the nuts 42 in such a manner that the stress is transmitted, in part at least, by the nut directly to the base. Thus, in the form shown in Fig. 8, I have formed the nut with 130

such an arcuate shape that the back 46 is adapted to wipe or rub against the base, as the nut is rotated with respect to the base.

If the pins 43 are loosely provided in the base, 5 the stress of the locking up will be transmitted directly through the nut into the base, the function of the pins then being only to hold the nut rotatably with respect to the base.

10 The variable positioning means of my invention may be modified to be useful with other types of plates such as those which are already mounted. In such an instance the clip may be omitted and the bolt 21 provided 15 with a suitable face for engaging the mounted plate, or the block upon which it is positioned, so that the plate may be readily varied within the form retaining means.

I claim:

20 1. As a new article of manufacture for use in securing a printing plate to a block and for moving the secured plate and block to a desired position, a clip having an inwardly extending lip and an inwardly extending projection spaced from said lip adapted to engage the block, and adjustable means secured to said clip to move said secured block and plate simultaneously to the desired position.

25 30 2. As a new article of manufacture for use in securing a printing plate to a block and for moving said block and said secured printing plate to a desired position comprising securing means for detachably securing said plate to the block, and adjusting means for moving said secured block and plate to the desired position.

35 3. As a new article of manufacture for use in securing a printing plate to a block and for moving the secured plate and block to a desired position, a clip adapted to engage the block to secure the printing plate detachably thereto, and screw means secured to said clip for moving said secured plate to 40 the desired position.

45 4. As a new article of manufacture for use in securing a printing plate to a block and for moving the secured plate and block with respect to furniture, means for securing 50 the plate detachably to the block, and means adapted to abut against said furniture and against said clip, said means being adapted to be moved to vary the position of said secured block and plate with respect to 55 said furniture.

55 5. As a new article of manufacture, means for securing a printing plate to a block, a base attached to said securing means, and means for adjusting said securing means 60 with respect to said base.

65 6. As a new article of manufacture, means for detachably securing a printing plate to a block in a form, a separate base for said securing means, said base being adapted to 70 be contacted with furniture in form retain-

ing means, and means for enabling movement of said securing means with respect to the base.

In testimony whereof, I have hereunto set my hand.

HARRY LEVISON.
